LOADING AND UNLOADING CRANE

August M. Delters, Atlanta, Ga., assignor to
Southern Wood Preserving Company, Atlanta,
Ga., a corporation of Georgia

Application January 22, 1945, Serial No. 573,884

9 Claims. (Cl. 212—55)

This invention relates to cranes and, among other objects, aims to provide a greatly improved crane for loading and unloading heavy objects from box cars and the like. The main idea is to provide a crane positioned adjacent to a railroad track and having a crank arm which is rotatable into the open door of a box car on the track, the crank arm carrying a rotatable frame or bracket on which is mounted a horizontally movable boom designed to be projected into the far corners of the car for loading and unloading heavy objects. Another aim is to provide, in a crane of this type, simple and efficient power operating means for the boom. Another important aim of the invention is to provide suitable means for elevating and lowering the crane according to the level of the load or the height of box car doors. Still another aim is to provide an improved mechanism for unloading crossties from railroad cars. Another object is to provide such a crane which, while being mounted on one side of the track, can expeditiously load and unload heavy objects through the side door of a box car remote from the crane. Another object is to provide means whereby parts of the crane can be readily swung inside of the open door of a box car and can as readily be swung out to permit the car to be moved into or out of loading position.

Other aims and advantages of the invention will appear in the specification when considered in connection with the accompanying drawings, wherein:

Fig. 1 is a plan view of an embodiment of the invention shown in operating position beside a box car;

Fig. 2 is a side elevation of the crane shown in Fig. 1, omitting the showing of the box car; and

Fig. 3 is a fragmentary section taken on the line 3—3 of Fig. 2.

The crane of the present invention is disclosed more or less diagrammatically in my co-pending application, Ser. No. 564,509, filed November 1, 1944, entitled "Method of and apparatus for handling crossties." It is to be understood, however, that the utility of this invention is not to be considered as limited to such particular use, as will be readily apparent to those skilled in the art of handling heavy loads.

Referring to the drawings, there is shown a crane embodying the invention having a rigid frame 10 firmly mounted beside a railroad track 11. In the illustrative example, the frame is secured by lag screws or bolts 12 secured in a concrete base or footing. The frame is of general tripod construction, having a pair of side legs 13

and a rear leg 14. A strut 15 serves as a cross brace. Horizontal plate members 16 and 17 are shown as being welded to the legs to complete the frame construction. In this example, the legs of the frame are made of structural beams joined together as by welding. However, it is contemplated that the framework supporting the crane may be mounted on wheels or a tramcar adapted to be anchored on a track, thereby making it possible to move the crane adjacent to a car instead of spotting a car adjacent to the crane.

A crank arm, designated generally by the numeral 18, is carried in sleeve bearings 19 and 20 mounted, respectively, in the webs of I-beams 21 and 22 welded to the vertical legs of the frame 10. The crank arm is formed of lengths of pipe welded as shown, and has a vertical post 23 rotatable in the bearings 19 and 20. Horizontal arms 24 carry, at their outer ends, a vertical length of pipe 25, which rotatably carries the boom 26, a supporting bracket 27 and associated mechanism. A screw jack 28 supports the lower end of the post or pivot member 23 and is used for vertically adjusting the position of the crank arm 18 in the bearings 19 and 20. The screw jack supports the vertical load of the moving parts of the crane together with any load being moved by the crane, and sleeve bearings 19 and 20 bear the side thrust exerted by the crank arm 18.

A pair of chain guys 29 are shown as being fixed to eyes 30 on the vertical pipe 25 of the crank arm and are removably secured to hooks 31 on the opposite ends of the lower beam member 21. The chains may be removed or unhooked to permit the crank arm to be swung to one side next to the legs of the frame 10 out of the way of the car.

The vertical pipe member 25 at the outer end of the crank arm carries a stem or shaft 32 mounted on an upper thrust bearing 33 and lower guide bearing 34. As best seen in Fig. 3, the thrust bearing 33 is of the roller type and has an outer raceway 35 and an inner raceway 36 which carries the stem 32. The lower bearing 34 is also of the tapered roller type and can be adjusted in the usual manner. A sleeve or short length of pipe 37 surrounds the shaft 32 and is welded thereon to rest upon the inner raceway 36 of bearing 33. The boom support 27 comprises a pair of vertically disposed plates 38 and 39 welded to opposite sides of the pipe 37. Pairs of vertically spaced rolls 40 and 41 at opposite ends of the support, guide the boom 26, which is preferably in the form of an H-beam to provide great bending resistance. The boom is free to reciprocate on the rollers 40 and 41 so that the boom may be pro-

jected or moved to any desired position within the car.

Means for reciprocating the boom includes a reversible electric motor 42 mounted on the bracket plate 38 and is provided with suitable switches or controls (not shown). The motor 42, through belt-drive 43 and shaft 44, drives a worm and wheel reducer 45. The speed reducer is connected to drive drums 46 and 47 at equal peripheral velocities and in the same direction by means of a suitable chain and sprocket drive 48. About the drum 46 a rope or cable 49 extends to eye 50 at the forward end of boom 26. Similarly, from the drum 47 a cable or rope 51 is connected to an eye 52 at the rear end of the boom. The motor 42, when driven in one direction, serves to wind up the cable 51 on the drum 47 and to unwind cable 49 from drum 46, thereby moving the boom in a forward direction. Reversal of the motor 42 effects a reversal of the rotation of the drums and a resultant rearward movement of the boom 26.

The boom 26 carries a suitable load hoisting means shown specifically as a hook 53 attached to a hoisting line or cable 54 passed over a system of pulleys 55, 56 and 57 to a hoisting drum 58. The drum 58 is driven by a reversible electric motor 59 through a belt drive 60 and worm and wheel speed reducer 61. Suitable switches or controls (not shown) are provided for the motor 59. It will be observed that rollers 40 and 41, which support the boom, are provided with central grooves through which cables 49, 51 and 54 may pass without interfering with the operation of the rollers in supporting and guiding the boom. The boom also carries ordinary limit switches (not shown) to stop the operating motor when the boom reaches the ends of its travel.

In operation, a box car 62 is stopped beside the crane with its near door 63 and its far door 64 adjacent to the crane. The crank arm 18 is vertically adjusted, if necessary, by means of the jack 28 so that it, together with the boom support, may be swung into position in the car door 63, as shown in Figs. 1 and 2, and locked in this position by engagement of the free ends of the chain guys 29. With the crank arm in this position, the boom support 21 may be manually rotated, as indicated by the arrows in Fig. 1, to assume a position where the boom may be projected into the farthest corners of the car, as shown in dotted lines in Fig. 1. Such horizontal rotation of the boom and support preferably is accomplished by an operator stationed within the car 62, but it will be understood that power means may be provided for rotating the boom and boom support. An article to be unloaded from the car is attached to hook 53, or other suitable load-engaging means, and is hoisted to be conveyed out of the car. The operator, by use of the motor 42, causes the boom to be retracted to approximately the position shown in solid lines in Fig. 1, and manually swings the boom and its load to a transverse position with respect to the car. Next, the operator projects the loaded boom out through the opposite car door 64 and operates the hoisting motor 59 to cause the load to be lowered to a platform, vehicle, or conveyor. It will be appreciated that, whereas the crane of this invention is particularly adapted for loading and unloading box cars, it may also be utilized for unloading flat cars, gondolas and the like.

From the foregoing description, it will be seen that this invention provides a unique and efficient device for loading and unloading box cars. It will be understood that various modifications

may be made in the embodiment of the crane herein shown and described without departing from the spirit of the invention as defined in the appended claims. Moreover it is not indispensable that all the features of the invention be used conjointly, since they may be employed advantageously in various combinations and sub-combinations.

What is claimed is:

1. A car loading and unloading crane of the character described, comprising, in combination, an upstanding support positioned adjacent to a railroad track; a crank arm carried by said support and mounted to swing horizontally into and out of operating position with respect to the opening of a box car door; a boom support carried by said crank arm and mounted to rotate about a vertical axis; a horizontal boom carried by said boom support and mounted for radially extensible and retractible movement so that it can be projected to any position in the box car; operating means connected to reciprocate the boom; and load hoisting means carried by the boom.

2. A car loading and unloading crane of the character described, comprising, in combination, an upstanding support adapted to be mounted adjacent to a railroad track; a crank arm carried by said support and mounted to swing horizontally into and out of operating position with respect to the opening of a box car door; means for vertically adjusting the position of said crank arm; a boom support carried by said crank arm and mounted to rotate about a vertical axis; a horizontal boom carried by said boom support and mounted for radially extensible and retractible movement so that it can be projected into and out of a box car; a motor connected to reciprocate the boom; and load hoisting means carried by the boom.

3. A car loading and unloading crane of the character described comprising, in combination, an upstanding support adapted to be rigidly mounted adjacent to a railroad track; a pair of vertically disposed bearings carried by said support; a vertical pivot member journaled in said bearings; a horizontal crank arm extending from said pivot member; a vertical bearing member carried by the end of said arm; means connected to raise and lower said pivot member; a vertical stem journaled for horizontal rotation carried by said bearing member; a boom support carried by said stem; a horizontal boom carried by said boom support and mounted for reciprocating movement so that it can be projected into and out of a box car; a motor connected to reciprocate the boom; and load-hoisting means carried by the boom.

4. A car loading and unloading crane of the character described comprising, in combination, an upstanding support adapted to be rigidly mounted adjacent to a railroad track; a pair of vertically disposed bearings carried by said support; a vertical pivot member journaled in said bearings; a horizontal arm extending from said pivot member; a vertical bearing member carried by the end of said arm; a jack for raising and lowering said pivot member; a vertical stem journaled for horizontal rotation in said bearing member; a boom support carried by said stem; a horizontal boom carried by said boom support and mounted for reciprocating movement so that it can be projected into and out of a box car; means to reciprocate the boom including a pair of drums carried by said boom support, a cable leading

from one of said drums to the forward end of the boom, a second cable leading from the other of said drums to the rear end of the boom, and a reversible motor connected to drive said drums at equal peripheral velocities to unwind one of said cables and wind up the other of said cables; and load-hoisting means carried by the boom.

5. A car loading and unloading crane of the character described comprising, in combination, an upstanding support adapted to be rigidly mounted adjacent to a railroad track, a pair of vertically disposed bearings carried by said support; a vertical pivot member journaled in said bearings; a pair of horizontal arms extending from said pivot member; a vertical bearing member carried by the ends of said arms; means connected to raise and lower said pivot member; a vertical stem journaled for horizontal rotation in said bearing member; a boom support carried by said stem; a horizontal boom carried by said boom support and mounted for reciprocating movement so that it can be projected into and out of a box car; means to reciprocate the boom including a pair of drums carried by said boom support, a cable leading from one of said drums to the forward end of the boom, a second cable leading from the other of said drums to the rear end of the boom, and a reversible motor connected to drive said drums at equal peripheral

velocities to unwind one of said cables and wind up the other of said cables; and load-hoisting means carried by the boom, including a pulley at the forward end of the boom, a hoisting drum at the rear end of the boom, a reversible motor for driving the hoisting drum; and a hoisting cable leading from the drum over the pulley at the forward end of the boom.

10 6. A crane, as set forth in claim 1, having means connected and arranged to adjust the height of the boom.

15 7. A crane, as set forth in claim 2, including a pair of chains carried by the crank arm and releasably connected to the support on opposite sides of the vertical axis of the crank arm, whereby the crank arm may be maintained in its horizontally adjusted position.

20 8. A crane, as set forth in claim 1, wherein the load hoisting means includes a motor and winding drum mounted on the rear end of the boom; and a hoisting cable trained over a sheave at the forward end of the boom.

25 9. A crane, as set forth in claim 2, wherein the motor for reciprocating the boom is a reversible electric motor supported by said crank arm; and reduction gearing connecting said motor to operate the boom.

A. M. DEITTERS.
